UNITED STATES PATENT OFFICE

ADOLPH R. REYNOLDS, OF COLUMBIA, SOUTH CAROLINA

BOTTLE FILLING MACHINE

Application filed February 16, 1932. Serial No. 593,332.

My invention relates to a counter-pressure liquid valve mechanism for use in filling bottles with liquids under pressure, such as carbonated beverages, and where it is desirable to have pressure in the bottle, its object being to provide a simple means and one which allows the placement of all principal parts on the exterior of the liquid tank so that repairs and replacements may be conveniently made.

With reference to the drawing, Figure 1 is a sectional view of the complete mechanism comprising my invention, showing the liquid valve in closed position.

Figure 2 is a fragmentary sectional view of the liquid valve and piston features of my device, showing said valve in open position.

Figure 3 is a fragmentary view in elevation of the device showing the casing of the piston feature of my invention, hereinafter explained in detail.

Referring to Figure 1, 1 designates the body member of the device having a fluid passage 2 through the center thereof, and is secured in an opening in the bottom of the liquid tank 3 by bolts or other conventional means, the washer or gasket 4 being compressed against said tank around said opening to prevent leakage therefrom.

The tube or pipe 5, the function of which will hereinafter be explained, extends upwardly through said body member 1, with proper packing to prevent leakage, and terminates above the liquid level in said tank.

Depending from said body member 1 is a member 6 comprising the liquid valve chamber 7, within which the ball 8 rests upon the shoulder of the fluid passage 9 through the center of the depending intermediate member 10, said passage 9 connecting with the filling tube 11, depending from said intermediate member 10.

Recesses in the underside of said member 10, and in the top side of connecting member 12, constitute a chamber 13 for the air valve 14 and spring 15, and acts as pressure connecting means with the lateral port 16 in said member 10. The air valve 14 is provided with a peripheral channel to make a tight

seat for said valve when held in position against the base of chamber 13 by the spring 15, over the pressure passage or inlet 17, and may be integral with or fastened to a sleeve 18 extending downwardly through said member 12 around the filling tube 11, being separated from the latter by an air passage 19.

Said sleeve 18 is provided with lateral ports 20, 20', so that by upward movement of said sleeve and air valve 14 the pressure entering lateral port 21 has access through the vertical pressure inlet 17 to the void created below the air valve by its upward movement, through the lateral ports 20, 20' in the sleeve 18, and by way of the passage 19 upwardly into the chamber 13 and lateral port 16.

The air valve 14 is operated by upward pressure from the head of the centering funnel 22, slidably arranged on the filling tube 11 and held thereon by the enlarged base 23 of the latter, against the sleeve 18. By this upward movement of the sleeve 18 and air valve member 14 pressure enters upwardly into the chamber 13 as described above, and downwardly through the air passage 19 surrounding the filling tube 11, through vertical air passage 24 in the centering funnel 22, and into the bottle to be filled. Tight connection between the member 12 and head of the centering funnel 22 is secured by contact of the latter with the gasket or washer 25, fastened to member 12. A similar gasket or washer may be used in the centering funnel in the usual manner to provide an air-tight connection with the bottle to be filled.

The operation of the liquid valve, comprising the chamber 7 and ball 8 closure for passage 9 to the filling tube 11, is accomplished by means of the horizontally movable plunger 26 and connected piston 27 within the cylindrical chamber 28 formed by the casing members 29 and 30. The piston 27 may be made air-tight by a piston ring 31, and its reverse movement facilitated by the spring 32.

As shown in Figure 1, when the horizontally movable plunger 26 is withdrawn from contact with the ball 8 by the movement of connected piston 27, the ball 8 rests over the

passage 9 to the filling tube 11, effectively preventing escape of the liquid in the tank.

As shown in Figure 2, when the plunger 26 is forced into contact with the ball 8 by the 5 forward stroke of the piston 27, the ball 8 is raised from its seated position over the liquid passage 9, and flow of liquid in the tank permitted through the liquid valve chamber 7, 10 passage 9, and filling tube 11, into the bottle.

10 As shown in Figure 1 and Figure 2, the pipe 33 connects the lateral port 16 in the intermediate member 10 and source of pressure with the casing 29 and chamber 28 on one side of the piston 27, while the pipe 15 5 and inlet 34 is arranged to likewise connect the chamber on the other side of the piston with a source of pressure. These pressures are required by the nature of the device to be so regulated that the pressure 20 through pipe 5 is less than the pressure entering the piston chamber 28 by way of the pipe 33. For this reason the pressure above the liquid may be used as the secondary (or lower) pressure, while an independent source 25 of pressure may be used as the primary (or higher) pressure.

From the foregoing description of the mechanical features of my device, it can be seen that when the centering funnel 22 is in the 30 position shown in Figure 1, the secondary pressure has forced the piston to the end of its chamber, withdrawing the plunger 26 from contact with the ball 8, and allowing it to seat over the liquid passage 9, thus closing 35 said passage to the filling tube 11.

With the upward movement of the centering funnel 22, and an airtight connection with the bottle or other container to be filled, the filling tube 11 enters the container, contact 40 of the funnel head with the sleeve 18 raises the air valve 14 until the funnel head rests against the gasket 25 and releases the primary pressure in the pressure inlet 21. By 45 the means hereinbefore described, the primary pressure is thereby established in the bottle, and at the same time causes a forward stroke of the piston 27 in chamber 28 and plunger 26 to unseat the ball 8, thus permitting 50 the liquid in the tank to enter the bottle.

With the downward movement of the funnel 22, the air valve 14 is seated over the pressure passage 17 and cuts off the primary pressure, while that primary pressure remaining 55 in the piston chamber 28 is released to the atmosphere through the pipe 33, port 16, chamber 13, and air passage 19. With the removal of the primary pressure, the secondary pressure through pipe 5 and inlet 34 60 to the piston chamber forces a counter-stroke of the piston 27, assisted by the spring 32, withdrawing the plunger 26 from contact with the ball 8, and allows said ball to seat over the liquid passage 9. Aided by the liquid 65 pressure from above, the ball 8 forms a

tight closure over the passage 9 and prevents the flow of liquid from the tank.

Having thus described my invention, I claim:

1. In a filling valve for a liquid tank, the combination of a valve casing having a liquid exit, valve and tank connecting means, an exit closing member freely disposed in said valve casing and arranged to close said exit under pressure of the liquid, a piston casing, 70 a piston in said casing, means connecting said piston casing with said valve casing, plunger means secured to said piston and adapted to unseat said exit closing member with the stroke of said piston, and pressure controlling means 75 whereby said piston is actuated. 80

2. In a filling valve for a liquid tank, the combination of a valve casing having a liquid exit, valve and tank connecting means, an exit closing member freely disposed in said valve casing and arranged to close said exit under pressure of the liquid, a piston casing, 85 a piston in said casing, means connecting said piston casing with said valve casing, a plunger secured to said piston, said plunger being 90 adapted to contact and unseat said exit closing member with the stroke of said piston, and pressure controlling means connected with the piston chamber. 95

3. In a filling valve for a liquid tank, the combination of a valve casing forming a valve chamber and having a liquid exit, tank and valve connecting means, an exit closing member freely disposed in said valve chamber and arranged to close said exit under pressure of 100 the liquid, a piston casing forming a piston chamber, a piston in said casing, means connecting said piston casing with said valve casing, a plunger in said connecting means and secured to said piston, said plunger being 105 adapted to contact and unseat said exit closing member with the stroke of said piston, and pressure controlling means connected with said piston chamber. 110

4. In a filling valve for a liquid tank, the combination of a casing forming a valve chamber and having a liquid exit, tank and valve chamber connecting means, a ball in said valve chamber seated in said exit, a piston casing forming a piston chamber, a piston in said casing, means connecting said piston casing with said valve casing, a plunger in said connecting means and secured to said piston, said plunger being adapted to contact and unseat said ball with the stroke of said 115 piston, and pressure controlling means connected with said piston chamber. 120

5. In a filling valve for a liquid tank, the combination of a casing forming a valve chamber, tank and valve chamber connecting means, a filling tube, means connecting said chamber with said filling tube, a ball in said valve chamber seated over said filling tube connecting means, a piston casing forming a piston chamber, a piston in said 125 130

casing, means connecting said piston casing with said valve casing, a plunger in said connecting means and secured to said piston, said plunger being adapted to contact and unseat said ball with the stroke of said piston, and pressure controlling means connected with said piston chamber.

6. In a filling valve for a liquid tank, the combination of a casing forming a valve chamber, tank and valve chamber connecting means, a filling tube, means connecting said chamber with said filling tube, a ball in said valve chamber seated over said filling tube connecting means, a piston casing forming a piston chamber, a piston in said casing, means connecting said piston casing with said valve chamber, a plunger in said connecting means and secured to said piston, said plunger being adapted to contact and unseat said ball with the forward stroke of said piston, pressure controlling means connected with said piston chamber above said piston, and counterpressure means connected with said piston chamber behind said piston.

25 7. In a filling valve for a liquid tank, the combination of a valve casing having a liquid exit, valve and tank connecting means, a filling tube depending from said liquid exit, a sleeve member slidably arranged on said filling tube, an exit closing member freely disposed in said valve casing and arranged to close said exit under pressure of the liquid, a piston casing, a piston in said casing, means connecting said piston casing with said valve casing, plunger means secured to said piston and adapted to unseat said exit closing member with the stroke of said piston, and pressure controlling means connected with said piston casing comprising a valve actuated by the movement of said sleeve member on said filling tube.

8. In a filling valve for a liquid tank, the combination of a valve casing having a liquid exit, valve and tank connecting means, a filling tube depending from said liquid exit, a sleeve member slidably arranged on said filling tube, an exit closing member freely disposed in said valve casing and arranged to close said exit under pressure of the liquid, a piston casing, a piston in said casing, means connecting said piston casing with said valve casing, a plunger secured to said piston, said plunger being adapted to contact and unseat said exit closing member with the stroke of said piston, and pressure controlling means connected with said piston casing comprising a valve actuated by the movement of said sleeve member on said filling tube.

9. In a filling valve for a liquid tank, the combination of a casing forming a valve chamber and having a liquid exit, tank and valve connecting means, a filling tube depending from said liquid exit, a sleeve member slidably arranged on said filling tube, an exit closing member freely disposed in said

valve casing and arranged to close said exit under pressure of the liquid, a piston casing forming a piston chamber, a piston in said casing, means connecting said piston casing with said valve casing, a plunger in said connecting means and secured to said piston, said plunger being adapted to contact and unseat said exit closing member with the stroke of said piston, and pressure controlling means connected with said piston chamber comprising a valve actuated by the movement of said sleeve member on said filling tube.

10. In a filling valve for a liquid tank, the combination of a casing forming a valve chamber and having a liquid exit, tank and valve chamber connecting means, a filling tube depending from said liquid exit, a sleeve member slidably arranged on said filling tube, a ball in said valve chamber seated in said exit, a piston casing forming a piston chamber, a piston in said casing, means connecting said piston casing with said valve casing, a plunger in said connecting means and secured to said piston, said plunger being adapted to contact and unseat said ball with the stroke of said piston, and pressure controlling means connected with said piston chamber comprising a valve actuated by the movement of said sleeve member on said filling tube.

11. In a filling valve for a liquid tank, the combination of a casing forming a valve chamber, tank and valve chamber connecting means, a filling tube, a centering bell slidably arranged on said filling tube, means connecting said valve chamber with said filling tube, a ball in said valve chamber seated over said filling tube connecting means, a piston casing forming a piston chamber, a piston in said casing, means connecting said piston casing with said valve casing, a plunger in said connecting means and secured to said piston, said plunger being adapted to contact and unseat said ball with the forward stroke of said piston, and pressure controlling means connected with said piston chamber comprising a valve actuated by the movement of said centering bell on said filling tube.

12. In a filling valve for a liquid tank, the combination of a casing forming a valve chamber, tank and valve chamber connecting means, a filling tube, a centering bell slidably arranged on said filling tube, means connecting said valve chamber with said filling tube, a ball in said valve chamber seated over said filling tube connecting means, a piston casing forming a piston chamber, a piston in said casing, means connecting said piston casing with said valve casing, a plunger in said connecting means and secured to said piston, said plunger being adapted to contact and unseat said ball with the forward stroke of said piston, pressure controlling means connected with said piston chamber comprising a valve actuated by the movement of said centering bell on said filling tube.

means connected with said piston chamber above said piston and comprising a valve actuated by the movement of said centering bell on said filling tube, and counterpressure connecting means connected with said piston chamber behind said piston.
